ROTARY ELECTRIC SWITCH

Richard B. Hunter, Shorewood, and Harold L. Mekelburg, Milwaukee, Wis., assignors to Cutler-Hammer, Inc., Milwaukee, Wis., a corporation of Delaware

Application August 9, 1941, Serial No. 406,132

7 Claims. (Cl. 74—565)

This invention relates to rotary electric switches such as drum controllers of the reversible type. Such controllers usually comprise a series of stationary contacts which cooperate with movable contacts, the latter being mounted on, and suitably insulated from a rotating shaft. The rotating shaft, with its contacts, generally called the drum, has considerable inertia. The drum is biased to an "off" position, and is provided with one or more operative positions on each side of the "off" position for connection of a motor, or other translating devices controlled thereby, for operation thereof in a forward or reverse direction, selectively.

The shaft may be operated in various conventional ways. It may, for instance, be provided with an operating handle for direct manual control. In this case the drum may be biased to the "off" position by a centering spring, or it may be provided with a star-wheel with notches or indentations cooperating with a suitable pawl to retain it in any one of the various operating positions or in the "off" position, respectively.

In other cases, the operating shaft is provided with a sheave wheel, over which a rope is wound by means of which the wheel is rotated alternately by pulling one or the other end of the rope. Such rope operated devices are usually provided with a centering spring, which biases the drum to the "off" position and returns it to the latter position from an operating position upon release of the rope.

An object of the invention is to provide means for preventing too rapid movement of devices of the aforementioned character from an operative position on one side of a neutral or "off" position, to an operative position on the other side of the "off" position.

Another object of the invention is to provide improved and simplified means for positively preventing too rapid movement of a multi-position controller from one operative position to any other operative position.

Another object of the invention is to provide means for positively preventing movement of devices of the aforementioned character from a given "on" position beyond an "off" position, in the event that the speed of movement thereof exceeds a predetermined normal rate.

Another object of the invention is to provide an anti-plugging device for a reversing switch or controller for a reversible electric motor.

Other objects and advantages will hereinafter appear.

The accompanying drawing illustrates one embodiment of the invention.

In the drawing,

Figure 1 is a fragmentary view (partly in section) of a reversing drum controller having our improved anti-plugging device applied thereto,—the latter being shown in bottom plan.

Fig. 2 is a fragmentary cross sectional view, on the line 2—2 of Fig. 1,—the stationary and movable contacts of the drum being shown more or less diagrammatically.

Referring to the drawing, the same shows an operating shaft 1 on which is mounted a series of movable contacts diagrammatically indicated by 2, which cooperate with stationary contacts 3 (see Fig. 2). The shaft 1 is rotatably supported in a bearing 4 of a top plate 5 of the drum controller, and is provided with a cam 6 which is fastened to the shaft to rotate therewith. The cam 6 has cam surfaces 7 and 8 which intersect each other at 9. The cam 6 is also provided with a rectangular notch or recess 10.

The cam surfaces 7 and 8 are arranged to cooperate with cam surfaces 11 and 12 of an inertia device generally designated as 13. The inertia device has an extension 14 which is adapted to enter the recess 10 of the cam 6. The inertia device 13 is rotatably supported on a pivot 15, which is mounted on the top plate 5.

The mass of the inertia device 13 is preferably so disposed that it is substantially balanced about the pivot 15 in all angular positions. A tension spring 16 is interposed between the inertia device 13 and a fixed point on the top plate 5, so as to bias the former, tending to rotate it in a counter-clockwise direction. The extent of such rotation is limited by an adjustable stop 17 carried by the top plate 5.

A helical spring 18 surrounds the shaft 1. The two straight ends of the spring 18 extend substantially radially and engage a pin 19 attached to the cam 6 and a pin 20 attached to the top plate 5, in such a manner that if the shaft is rotated in one or the other direction, the pin 19 tends to rotate one or the other end of the spring 18 to wind it tighter and to increase its tension, the pin 20 under these conditions acting to hold the other end of the spring against rotation, as will be obvious. As a result, the spring 18 always tends to return the shaft 1, with its cam 6, to the "off" position, which is the position of the cam shown in the drawing in full lines. A handle 21 is provided to rotate the shaft 1.

The device operates in the following manner:

With the drum in one of its "on" positions,

when either of the cam surfaces 7 or 8 engages the cam surfaces 11 or 12, respectively, it tends to rotate the inertia device 13 in a clockwise direction against the bias of the spring 16, until the device is in the position shown in full lines in Fig. 1. In this position the cam 6 and with it the shaft 1 may be rotated in either direction by means of the handle 21. Such rotation frees the inertia device 13, and permits it to rotate counterclockwise to the dotted line position. After being rotated from the neutral position in either direction, the shaft 1 may now be further rotated as far as is desired, without interference between cam 6 and the inertia device 13. If, however, the shaft 1 and with it the cam 6 are returned at a high or abnormal rate of speed from an operative position, such as either one of the operative positions of cam 6 shown in dotted lines in Fig. 1, to the neutral position, the impact between the cam surfaces 7 and 11 or surfaces 8 and 12, respectively, causes the inertia device to be rotated clockwise, tending to carry it beyond the full line position shown in Fig. 1 until the extension 14 enters the recess 10 when the latter is opposite to the former, and thereby prevents further rotation of the cam 6, until the kinetic energy stored up in the inertia device 13 has been dissipated, whereupon the biasing spring 16 tends to rotate it counterclockwise, the cooperating cam surfaces, on cam 6 and inertia device 13, then serving to hold the latter in the full line position thereof illustrated. With the parts so positioned, the cam 6 and drum shaft 1 may be rotated from the intermediate or neutral position in either direction at any desired speed.

When no rotative force is applied to handle 21 at the time of engagement of inertia device 13 with recess 10, the action of spring 18 serves to release pressure upon the extension 14 of inertia device 13, thereby facilitating counterclockwise rotation of device 13 by spring 16; whereas if rotative force is continuously applied to handle 21 the aforementioned result may be attained by a reduction of the rotative force, which enables spring 16 to overcome the friction of engagement of extension 14 of said inertia device with a wall of recess 10.

The positions of the cam surfaces and recess of the cam 6 relatively to the cam surfaces and extension of the inertia device 13 may readily be adjusted by adjustment of the stop 17, to provide for wear and variations in alignment.

The use of the present invention is particularly advantageous in connection with rope operated reversing switches and the like which are biased to an "off" position by a powerful spring. In the past such devices had to be provided with friction brakes or the like (due to weight of the movable parts and the consequently necessary force of the spring) to retard their movement through the "off" position in the event of manual release of the rope in one of the running positions. The present invention, however, automatically prevents plugging without requiring retarding means of the type which depend upon the uncertain effects of friction and which experience shows is greatly variable and uncertain.

We claim:

1. In a reversing controller, an operating shaft having an "off" position and rotatable to a running position on either side of said "off" position, a member attached to said shaft to rotate therewith and provided with an abutment and a single recess, an inertia device rotatably supported on a stationary pivot and provided with a dog

adapted to engage said recess to lock said shaft against rotation in its "off" position under certain conditions, and alternatively to automatically engage said abutment when said shaft is rotating within a given angular range adjacent to both sides of said "off" position, and a spring biasing said inertia device to normally hold said dog out of engagement with said recess, said abutment and said inertia device being further arranged to cause said inertia device to rotate and carry said dog into engagement with said recess upon return of said shaft from either operative position to the "off" position above a given speed.

2. In a reversing controller, a contact mechanism having an operating shaft oscillatable from an "off" position to a running position on either side of said "off" position, a cam attached to said shaft and having an abutment and a recess, an inertia device oscillatable about a stationary pivot and adapted in one position to engage said recess when said shaft is in its "off" position to lock the same against rotation, a spring normally biasing said inertia device out of engagement with said recess, means for limiting the degree of movement of said inertia device under said bias, and an abutment on said inertia device adapted to engage said first named abutment when said shaft is within a given angular position on either side of said "off" position to move said inertia device against the bias of said spring and to temporarily engage said recess under the influence of an impact between said abutments.

3. In a reversing drum controller, a contact mechanism having an operating shaft oscillatable from an "off" position to a running position on either side of said "off" position, a cam attached to said shaft and having an abutment and a recess, an inertia device oscillatable about a stationary pivot and adapted in one position to engage said recess when said shaft is in its "off" position to lock the same against rotation, a spring normally biasing said inertia device out of engagement with said recess, adjustable means for limiting the degree of movement of said inertia device under the bias of said spring, and an abutment on said inertia device adapted to engage said first named abutment when said shaft is within a given angular position on either side of said "off" position to move said inertia device against the bias of said spring and to temporarily engage said recess under the influence of an impact between said abutments.

4. In a reversing drum controller, in combination, an operating shaft having an intermediate "off" position and rotatable to an "on" position on each side of said "off" position, associated means including a cam member positively rotatable with said shaft and an inertia member having a point of pivotal support fixed relatively to said cam member, and said cam and inertia members having cooperating parts, said cooperating parts comprising a pair of cam surfaces on said inertia member and a pair of cooperating cam surfaces and a single recess on said cam member and a single dog on said inertia member and cooperating with said recess to positively prevent movement of said shaft from either "on" position beyond said intermediate "off" position, in the event that the speed of such movement exceeds a predetermined normal rate.

5. In a reversing drum controller, an operating shaft having an "off" position and rotatable to a running position on either side of said "off"

position, a member attached to said shaft to rotate therewith and provided with an abutment in the form of a double-inclined cam and a single recess, an inertia device rotatably supported by a stationary pivot, said inertia device having a portion in the form of a double-inclined cam for cooperation with said first mentioned cam, a spring associated with said inertia device to normally bias the cam of the latter into engagement with said first mentioned cam, and said inertia device having another portion in the form of a lug engageable with one wall or another of said recess under given conditions, the arrangement being such that said shaft may be rotated from "off" position to either running position at any speed and from either running position to the other at or below a predetermined speed without interference by said inertia member, the latter acting to lock said shaft in "off" position when the movement thereof from a running position is at a rate above said predetermined speed.

6. In a reversing drum controller, an operating shaft having an "off" position and rotatable to a running position on either side of said "off" position, a member attached to said shaft to rotate therewith and provided with an abutment in the form of a double-inclined cam, an inertia device rotatably supported by a stationary pivot, said inertia device having a portion in the form of a double-inclined cam for cooperation with said first mentioned cam, a spring associated with said inertia device to normally bias the cam of the latter into engagement with said first mentioned cam, and means arranged on said member and on another portion of said inertia device and adapted to permit rotation of said shaft from "off" position to either running posi-

- tion at any speed and from either running position to the other at or below a predetermined speed without interference by said inertia member, the latter acting to temporarily lock said shaft in the "off" position when the movement thereof from a running position is at a rate above said predetermined speed, said means comprising a single recess and a lug engageable with one wall or another of said recess under given conditions.
7. In a reversing drum controller, an operating shaft having an "off" position and rotatable to a running position on either side of said "off" position, a member attached to said shaft to rotate therewith and provided with an abutment in the form of a double-inclined cam, an inertia device rotatably supported by a stationary pivot, said inertia device having a portion in the form of a double-inclined cam for cooperation with said first mentioned cam, a spring associated with said inertia device to normally bias the cam of the latter into engagement with said first mentioned cam, and a lock arranged on said member and on another portion of said inertia device and comprising a single recess and a lug engageable with one wall or another of said recess under given conditions and adapted to permit rotation of said shaft from "off" position to either running position at any speed and from either running position to the other at or below a predetermined speed without interference by said inertia member, the latter acting to temporarily lock said shaft in the "off" position when the movement thereof from a running position is at a rate above said predetermined speed.
